[57] **CLAIM**

The ornamental design for a bed, as shown and described.

DESCRIPTION

FIG. 1 is a perspective view of a bed showing my new design;

FIG. 2 is a side view, the opposite side view being a mirror image thereof;

FIG. 3 is a front elevational view thereof;

FIG. 4 is an enlarged partial side elevational view of the post top;

FIG. 5 is a rear partial perspective view of the footboard with the top broken away to show indefinite height and termination.

The broken lines are for environmental purposes only and form no part of the claimed design.
